UNITED STATES PATENT OFFICE.

HENRY S. LOCKMAN, OF CASTLETON, NEW YORK.

PUMP.

SPECIFICATION forming part of Letters Patent No. 593,809, dated November 16, 1897.

Application filed January 9, 1896. Serial No. 574,836. (No model.)

To all whom it may concern:

Be it known that I, HENRY S. LOCKMAN, of Castleton, county of Richmond, State of New York, have invented a certain new and useful 5 Improvement in Pumps, of which the following is a specification.

This invention involves a construction for a pump requiring but few parts and producing a pump adapted to lift and discharge large 10 volumes of liquid.

I will describe a pump embodying the features of my invention, and then point out its novelty in a claim.

In the accompanying drawings, Figure 1 is 15 a plan view of a pump embodying my invention. Fig. 2 is a vertical cross-section of the same.

Similar letters of reference designate corresponding parts in both figures. 20 The casing of the pump is in the present instance shown as consisting of an upper part A, constituting the piston-chamber, and a lower part B, constituting the supply-chamber. The parts of the casing may be secured 25 together by bolts, as shown, or by other fastening devices. The lower part B of the casing is in this instance provided with a screw-threaded opening for the attachment of a supply-pipe. (Not shown.) From the supply- 30 chamber communication is had with the piston-chamber at opposite sides of the latter through openings controlled by valves C and C, respectively. As shown, each valve C consists of a body c and a facing c', of leather or 35 similar material, secured at the base of the piston-chamber by a clamping-piece c². The interior or working side surfaces of the piston-chamber are cylindric in form, the piston-chamber being closed at the ends by suitable 40 end plates extending transversely from the side portions of the cylinder.

D is the piston, comprising rectangular plates d d, here shown as formed integrally in one piece and radiating upwardly from 45 the bottom surface of the piston-chamber. This piston is intended to have a vibratory movement in the arc of a circle about an axis coincident with that of the cylindric inner surface of the piston-chamber. The bearing 50 forming the support for the piston D in the present case is formed by the convex surface of a longitudinal piece E, over which fits a

corresponding longitudinal recess E' at the bottom of the piston. This form of bearing or movable seat for the piston has the advantage that no cutting of the sides of the piston-chamber is necessary to support the piston, and consequently there is no leakage; and, furthermore, from the present construction and arrangement the removal of the piston 55 from its chamber is more easily effected, it being simply necessary to disconnect the lower or supply chamber, whereupon the piston and its appurtenances will be lowered, and can readily be taken out for repair or for 60 other purposes. It is to be observed that the bearing-piece E is centrally mounted upon the division-plate K, which separates the piston and supply chambers, so that the disconnection of said latter chamber effects the lowering of the piston. If desired, however, the 65 said supply-chamber may be made separate from the division-plate and the two separately removable, and thus the removal or disconnection of the supply-chamber would not of necessity effect the lowering of the piston. 70 This same form of bearing or movable seat is easily adapted to vibrating pistons of other form than that shown, but the construction shown is the preferred form of piston. It is 75 evident that the construction of the longitudinal recess at the bottom of the piston and the longitudinal bearing-piece E could be simply reversed and still operate in substantially the same way. These and other similar changes could of course be made and still be within the scope of my invention. 85

Packing-strips e are secured to the edges of the plates d d, forming the piston and bear against the inner surfaces of the piston-chamber. Each plate d is provided with a transverse opening d', controlled by a valve d², whose general construction may be the same as already described with reference to the valves at the bottom of the piston-chamber. 90

F is a cross-brace extending between and secured to the outer edges of the plates d d. It constitutes as well an additional support for a rod G, secured at its extremity to the 95 piston D and extending upwardly therefrom and providing means for effecting the necessary vibration to the piston. Said cross-brace also serves to hold the valve d² securely in 100

place upon the upper surfaces of the plates, as shown. The upper portion of the casing A is cut away and the edges of the opening extended upward by flanges *g* on three sides. 5 The remaining edge of the opening is extended outwardly in the form of a discharging-spout *g'*.

The operation of the pump is evident from an inspection of Fig. 2. When the piston 10 D swings to the left, the liquid imprisoned in the piston-chamber at the left closes the valve C at the left and raises the valve *d*², the liquid therefore passing above the piston in the direction of the discharge. At the opposite 15 side of the piston-chamber the reverse operations are taking place, liquid being drawn into the piston-chamber, as shown by the arrow at the right. As the direction of movement of the piston changes, the several 20 valves assume their opposite positions, resulting in a rise of the liquid to the discharge-opening and its ultimate discharge.

Having described my invention, what I consider as new, and desire to secure by Letters 25 Patent, is—

The combination in a pump, of a piston-chamber cylindric in form and having in its

top a flanged discharge-opening and a spout, a removable supply-chamber having a top plate constituting the bottom of the piston-chamber and provided at opposite points with hinged valves opening into said piston-chamber, a convex bearing-strip extending diametrically across the top plate intermediate its valves, and a vibrating piston constituted of plates substantially equal to the radius of the piston-chamber and uniting with each other at an angle and each having an upwardly-opening valve, the said piston being provided on its upper side near the ends 30 with a cross-brace, which secures the valves of the plates in place and having an operating-rod fastened at its lower end to the piston and passing through an opening in the center of the cross-brace, substantially as 35 shown and for the purpose described.

In testimony whereof I have signed my name to this specification in the presence of two subscribing witnesses.

HENRY S. LOCKMAN.
